(57) **CLAIM**

The ornamental design for a control panel, as shown and described.

DESCRIPTION

FIG. 1 is a perspective view of the control panel;

FIG. 2 is a front view of the control panel;

FIG. 3 is a right side view of the control panel;

FIG. 4 is a left side view of the control panel;

FIG. 5 is a bottom view of the control panel; and,

FIG. 6 is a top view of the control panel.

The elements and structures shown in dashed lines are shown for illustration purposes only and do not form part of the design.
